UNITED STATES PATENT OFFICE.

JULIUS H. SCHLAFLY, OF CANTON, OHIO, ASSIGNOR TO THE BERGER MANUFACTURING COMPANY, OF CANTON, OHIO.

TUBE-FORMING MACHINE.

SPECIFICATION forming part of Letters Patent No. 766,531, dated August 2, 1904.

Application filed March 28, 1902. Serial No. 100,488. (No model.)

To all whom it may concern:

Be it known that I, JULIUS H. SCHLAFLY, a citizen of the United States, residing at Canton, in the county of Stark and State of Ohio, have invented certain new and useful Improvements in Tube-Forming Machines; and I do hereby declare that the following is a full, clear, and exact description of the same, reference being had to the annexed drawings, making a part of this specification, and to the figures of reference marked thereon, in which—

Figure 1 is an end view showing a transverse section of the mandrel and the track or way, except the housing for the skelp-removing mechanism, which device is not illustrated. Fig. 2 is a vertical longitudinal section showing the machine broken in cross-section. Fig. 3 is a transverse section of the mandrel, the folding-heads, and one of the lower folding-head-operating cams. Fig. 4 is a perspective view showing a transverse section of the mandrel, illustrating the pipe or skelp located thereon and the device for locking the hooked edges of the skelp together. Fig. 5 is a view showing a portion of the main power-shaft, its clutch power - wheel, and the various sprocket driving-wheels, also showing a portion of the track or way and one of the end sprocket-wheels and a portion of the skelp-removing driving-chain. Fig. 6 is a view showing the skelp-removing power-shaft, together with its clutches and one skelp-removing driving-chain sprocket - wheel and the power-wheel. Fig. 7 is a front end view showing one of the skelp-removing driving-chain sprocket-wheels and its housing. Fig. 8 is a rear end view.

The present invention has relation to tube-forming machines designed and calculated to provide for connecting the previously folded or hooked edges together into a cylindrical tube, the present invention having special reference only to the folding or forming the hooked edged strip of metal into a cylinder and locking the hooked edges together; and it consists in the different parts, arrangement, and combination of parts hereinafter described, and particularly pointed out in the claims.

Similar numerals of reference indicate corresponding parts in all the figures of the drawings.

In the accompanying drawings, 1 represents the mandrel-supports, which are held in fixed positions and also provide proper supports for the skelp-removing mechanism and the track or way, which parts will hereinafter be more particularly described.

The mandrel 2 is located between the supports 1 and is supported at either end and is formed of a length to correspond substantially with the extreme length of any desired pipe designed to be formed, reference being had to the proper operation of the various devices for forming the skelp or tube and removing the same from the mandrel after it has been brought into a cylindrical form and the hooked edges locked together.

Directly below the mandrel 2 is located the lower folding-head 3, which lower folding-head is arranged to slide up and down in the guideways 4, said guideways being formed in the upper ends of the standards 5, which standards are spaced a distance apart equal to the width of the lower folding-head 3, or substantially so.

The top or upper edge of the lower folding-head 3 is provided with the concave groove 6, which concave groove is covered with a metal plate 7, which metal plate is formed to fit the concave groove 6, as illustrated in Figs. 4 and 5. The curvature of that portion of the metal plate 7 located in the groove 6 is of course to correspond substantially with the curvature of the outer periphery of the mandrel 2.

Below the lower folding-head 3 is located the shaft 8, which shaft is journaled in proper supports 9 and upon which shaft are securely fixed any desired number of cams 10, which cams are for the purpose of imparting an upward movement to the lower folding-head 3, and thereby bring the upper concave surface of the plate 7 against the metal designed to be operated upon, which metal is located between the top of the folding-head 3 and the bottom of the mandrel 2, as best illustrated in Fig. 1.

For the purpose of reducing the friction of

the cams 10 antifriction-rollers 11 are provided, which antifriction-rollers are journaled upon shafts 12, which shafts are held in proper position by the flange-plates 13, said flange-plates being securely attached to the bottom or under side of the folding-head 3.

For the purpose of imparting rotary motion to the shaft 8 and the cams 10 connected thereto to the sprocket-wheel 14 is provided, which 10 sprocket-wheel is securely fixed to the shaft 8 in any convenient and well-known manner and is driven by the drive-chain 15, said drive-chain leading to and around the sprocket-wheel 16, which sprocket-wheel is mounted 15 upon the shaft 17 and upon which shaft is mounted the sprocket-wheel 18, which is driven by the drive-chain 19, said drive-chain leading to the sprocket-wheel 22, upon the shaft of which is mounted the sprocket-wheel 20, 20 and from thence leads the drive-chain 22^b to the sprocket-wheel 20, located upon the main power-shaft 21, and for the purpose of bringing the drive-chains 19 and 22^b out of the way the wheels 22 and 22^a are located and arranged substantially as shown in Fig. 1 and 25 are both mounted upon the shaft 21^a, said shaft being journaled in suitable bearings connected to any fixed object.

It will be understood that when the power-shaft 21 is rotated the folding-head 3 will be elevated by means of the cams 10, which rotation takes place after the sheet from which the pipe is to be made is brought or placed on the top of the folding-head 3 and bridges the 30 groove 6, as illustrated in Fig. 1, and when the folding-head 3 is brought up it will bend the strip of metal around the bottom or under side of the mandrel and press the same between the metal plate 7 and said mandrel, 35 this being the first operation of the folding or bending the material to produce a cylindrical pipe.

Upon either side of the mandrel 2 are located the shafts 23 and 24, which shafts are 40 each provided with the sprocket-wheels 25 and 26. The shafts 23 and 24 are each journaled in proper supports 27 and 28, which supports are held in proper position by the standards 45 or their equivalents.

50 The shafts 23 and 24 are provided, respectively, with the slotted cranks 29 and 30, to which slotted cranks are adjustably connected the wrist-pins 31 and 32, to which wrist-pins are journaled the pitmans 33 and 34, which 55 pitmans are formed in sections and the sections connected together by screw-threaded coupling-heads 35, by which arrangement the pitmans can be adjusted as to length, this being necessary for the purpose hereinafter described.

Upon the tops or upper ends of the standards 5 are located the sliding heads 36 and 37, said sliding heads being located in ways 38.

To the sliding heads are securely connected 65 the side-folding heads 39 and 40, which side-

folding heads are connected in any convenient and well-known manner to the pitmans 33 and 34, and of course a backward and forward movement is imparted to the folding-heads 39 and 40 by means of the pitmans 33 and 34 and their connections.

To the folding-head 39 is connected the folding-plate 41, which folding-plate is so located that as it is moved toward the mandrel 2 after the lower folding-head has given the 75 sheet from which the pipe is to be made the first bend it will give that side of the sheet a bend around and over the top of the mandrel.

The folding-head 40 is brought toward the mandrel, together with its folding-plate 42, 80 and the folding-plate 42 comes in contact with the opposite side of the sheet from that engaged by the folding-plate 41 and bends the sheet over the top of the hooked edge and brings the hooked edges in such a position 85 that they can be locked together, and in order that the edges of the pipe may be properly hooked together the folding-heads are so timed that the folding-plate 41, together with its folding-head, will recede in time to 90 allow the folding-plate 42 to come over and carry with it the upper hooked edge of the sheet past the lower hooked edge thereof, the latter being still held to the mandrel, as the receding plate 41 will not up to this time have 95 released said lower hooked edge, and in order to properly hook the edges together the head 39 is provided with any desired number of arms or bars 43, to which arms are journaled rollers 44, which rollers are so located that 100 they will come over the top of the hinged portion of the folding-plate 42, by which arrangement the folding-plate 42 is pressed downward by reason of the inclined edge 45 of the folding-plate 42 coming under the 105 rollers 44, said rollers being held in a rigid position.

It will be understood that after the hooked edges of the sheet from which the pipe is to be made are locked together and the folding heads and plates withdrawn the pipe will remain upon the mandrel until removed therefrom, as hereinafter described.

For the purpose of normally holding the folding-plate 42 in an elevated position it is 115 hinged to the angle-bar 46 or its equivalent and the springs 47 provided, which springs are fixed to the angle-bar 46 and are extended under the hinged folding-plate 42, as illustrated in Fig. 4.

120 It will be understood that the cams 10 and the cranks 29 and 30 should be so adjusted that when a uniform rotary movement is given to the shafts upon which these parts are mounted the lower folding-head 3 will be brought into action first, the folding-plate 41 second, and the folding-plate 42 last, this being done by the proper adjustment of the different parts above referred to.

It will be understood that when the sheet 130

from which the pipe is to be made is fed onto the lower folding-head 3 the mechanism for folding the pipe is at rest, but when the sheet has been brought into its proper position to be acted upon the clutch 48 is thrown into engagement, so as to impart rotary motion to the power-shaft 21 by means of the operating-lever 49, and after the various parts have performed their function to produce a cylindrical pipe the clutch is drawn out of engagement and the power-shaft 21 brought to a stop, this being brought about by means of the power-wheel 50, running idle upon the shaft 21 when the clutch is disengaged.

15 The clutch 48 may be of any ordinary construction and may consist of a friction or an interlocking clutch, as desired.

Directly above the mandrel 2 is located the track or way 51, which track or way is supported at its ends by suitable uprights 52 or their equivalents. Upon the track or way is located a traveling carriage or head 53, which traveling carriage or head is connected to the lower member of the drive-chain 54 by means 20 of the bar 55 or its equivalent. To the bottom or under side of the head 53 is connected the hinged push-head 56, to which push-head is adjustably attached the push-plate or stripper 57, which stripper is for the purpose of 25 removing the skelp from the mandrel 2 as the carriage or head 53 is moved along the track or way 51. At the ends of the track or way are located the housings 58 and 59, and to the housing 58 is properly journaled and supported the shaft 59^a, and upon this shaft is mounted the sprocket-wheel 60, said shaft also being provided with the pulley 61, from which pulley leads the belt 62 to the pulley 63, which pulley is fixed to the shaft 64 and upon which 30 shaft are located the two driving-pulleys 65 and 66, said driving-pulleys being driven in opposite directions, preferably by open and crossed belts, and between the pulleys 65 and 66 is located the clutch 67, which clutch is drawn out 35 of engagement or into engagement with the desired pulley 65 or 66 by means of the operating-lever 68. The operation of this part of the machine is as follows: When it is desired to remove a skelp from the mandrel 2, the 40 shaft 64 is rotated in the direction that will move the head or carriage 53, together with its parts, including the stripper 57, toward the rear end of the machine, or, in other words, to the right in Fig. 2, the skelp moving off the mandrel 2 between the rollers 69 and 70. When the carriage is moved the desired length or distance, it is brought back to its normal position by the shifting of the clutch 67, when it is in proper position to remove from the mandrel another pipe. It will be understood that the pipe just in the rear of the last one made will be pushed entirely off the mandrel at the time the one last made is being removed. The drive-chain 54 extends 45 around the sprocket-wheels 60 and 71, and for

the purpose of holding the chain 54 in proper condition as to tension the shaft 72 of the sprocket-wheel 71 is journaled in the hinged bar 73, which hinged bar is adjusted by means of the screw-threaded bolt 74, which screw-threaded bolt abuts against the housing 59, substantially as illustrated in Fig. 2.

For the purpose of imparting rotary motion to the shafts 23 and 24 the drive-chains 25^a and 26^a are provided, which drive-chains 5 lead to the sprocket-wheels 20^a and 20^b, the sprocket-wheels 20^a and 20^b being mounted upon the power-shaft 21.

In order that the strip from which the pipe is to be made or formed may be properly guided so as to bring it into proper position with reference to the lower folding-head 3, the guide-flanges 7^a are provided, which guide-flanges are connected to the standards 5 or their equivalents.

It will be understood that in order to properly adjust the pitmans 33 and 34, so as to give to the folding-heads 39 and 40, together with their folding-plates, the exact movement to properly act upon the sheet from which the pipe is to be made it is very important that said pitmans should be properly adjusted not only as to the throw of the wrist-pins 31 and 32 to impart a longer or shorter stroke to the pitmans, but also to the distance between the extreme inner throw of the wrist-pins and the final stopping-point of the folding-plates, this being necessary that the proper locking of the hooked edges may be brought about, and in order to do this the coupling-links 35 are provided, by which arrangement a fine and accurate adjustment can be made and at the same time the folding-plates 41 and 42 brought into true parallel positions with reference to the mandrel.

Having fully described my invention, what I claim as new, and desire to secure by Letters Patent, is—

1. In a tube-forming machine, a mandrel held in fixed position, a central, reciprocating, folding-head provided with a concaved face, means for imparting a reciprocating movement to said folding-head, lateral folding-heads provided with folding-plates, one of the folding-plates being capable of yielding movement, and means for imparting a reciprocating movement to the lateral folding-heads and their plates, substantially as and for the purpose specified.

2. In a tube-forming machine, the combination of a mandrel, lateral folding-heads adapted to move to and from the mandrel, one of the folding-heads carrying a fixed folding-plate and another carrying a yielding folding-plate, and means for deflecting the yielding folding-plate, substantially as and for the purpose specified.

3. In a tube-forming machine, a mandrel, a reciprocating folding-head provided with a hinged folding-plate, said hinged folding-plate

provided with an inclined upper surface, a reciprocating head provided with a fixed folding-plate, arms carrying rollers and the rollers located in a plane above the lowest point 5 of the inclined portion of the hinged folding-plate, substantially as and for the purpose specified.

4. In a tube-forming machine, the combination of a frame, a mandrel carried by the frame, 10 folding-heads located adjacent to the mandrel, the central one of said folding-heads provided with a concave face and the two lateral folding-heads provided with folding-plates, one of which is yielding, a track or way having 15 mounted thereon a traveling head or carriage, and the traveling head or carriage provided with a stripper, substantially as and for the purpose specified.

5. In a tube-forming machine, the combination of a frame, a track or way, and a carriage 20 mounted thereon, said carriage provided with a stripper, sprocket-wheels mounted upon shafts located at the opposite ends of the track

or way, and the shaft of one of the sprocket-wheels journaled in an adjustable hinged bar 25 or frame, substantially as and for the purpose specified.

6. In a tube-forming machine, the combination of a frame and a mandrel in fixed position, lateral folding-heads slidably mounted 30 upon a frame and provided with folding-plates, parallel shafts provided with cranks and the cranks provided with adjustable wrist-pins, pitmans connected to the folding-heads and to the wrist-pins and the pitmans provided with coupling-heads adapted to adjust the length of the pitmans, and means for imparting rotary motion to the parallel shafts, substantially as and for the purpose set forth. 35

In testimony that I claim the above I have 40 hereunto subscribed my name in the presence of two witnesses.

JULIUS H. SCHLAFLY.
